UNITED STATES PATENT OFFICE

IAN MACDONALD, OF MODESTO, CALIFORNIA

COLLAPSIBLE SUPPORTING FRAME FOR TABLE AND SEAT UNITS

Application filed September 15, 1932. Serial No. 633,222.

This invention relates to collapsible table and seat units and particularly represents improvements over the frame structure shown in my co-pending application for Patent, Serial No. 624,388, filed July 25, 1932. My main objects now are to construct and arrange the parts of the collapsible frame in such a manner that such construction is simplified and the cost of manufacture lessened; 10 the frame when set up will present a neater appearance; and lighter material without sacrifice of rigidity and strength may be used than was the case with the previous structure.

A further object of the invention is to produce a simple and inexpensive device and yet one which will be exceedingly effective for the purpose for which it is designed.

These objects I accomplish by means of such structure and relative arrangement of 20 parts as will fully appear by a perusal of the following specification and claims.

In the drawings similar characters of reference indicate corresponding parts in the several views:

25 Fig. 1 is a perspective view of the assembled structure including the table and seats.

Fig. 2 is a similar view of the supporting framework alone shown as partly collapsed or folded.

30 Fig. 3 is a side view of the frame structure fully folded.

Figs. 4 and 5 are fragmentary views showing the detachable connection means between the horizontal frame bars and the corner legs.

35 Fig. 6 is a fragmentary plan view showing the supporting engagement of the table with the adjacent ends of a pair of the frame uprights or diagonals.

Fig. 7 is a perspective view of the table 40 partly folded showing the seats and the folded leg unit therein.

Referring now more particularly to the characters of reference on the drawings, the frame structure defines a square area and is 45 of the same general shape as in said above

mentioned co-pending application. It comprises four square corner legs 1 of a convenient seat height. Extending upwardly and toward each other from the bottom of adjacent legs on their outer sides are diagonal 50 bars 2. The adjacent upper ends of these diagonals are connected together on their inner faces by a downwardly folding strap hinge 3, while the lower ends are connected to the legs at the bottom by bolts 4.

Extending between the different pairs of adjacent legs in front of the diagonals and substantially on the same level when outstretched as the top of the legs are bar units 60 each comprising a pair of bars 5 of the same length. These are connected at their adjacent ends by an upwardly folding strap hinge 6 on the outside and are pivoted to the diagonals at their points of crossing by rivets or bolts 7.

By means of the above arrangement of parts it will be seen that the horizontal bar units limit the divergence and consequently the lowering of the diagonals without interfering with the upward folding movement 70 of the same. The divergence of the latter is also limited by the engagement of the upper ends of cooperating diagonals with each other when they are opened up or in operative positions.

The bars of adjacent units at the corners of the frame structure terminate in somewhat spaced relation to each other as shown in Fig. 5, being connected on their inner faces by rigid right angle straps 8 pivoted at their 80 ends to the bars by bolts or rivets 9 extending therethrough. Secured to the corners of the legs below the bars are vertical strips 10 formed with a lateral outwardly extending offset intermediate their ends so that the 85 hinge straps 8 at their exposed corners between the corresponding bar members may project between the legs and upper portions of the straps 10, as plainly shown. The space 90 between the upper portion of said straps and

the legs is less than the thickness of the diagonals 2, which are disposed between the legs and bars 5.

When the hinge straps are engaged between the legs and the straps 10 therefore said legs are sprung outwardly somewhat thus placing the parts under a certain tension and aiding in establishing and maintaining rigidity of the extended frame. This springing of the legs of course also tends to spring the bars and diagonals somewhat which also aids in giving them rigidity. This feature allows lighter stock for the frame members to be used than is otherwise the case without any lessening of strength and rigidity.

In addition the bars 5 serve to support the triangular seat boards 11 which are located against horizontal shifting by reason of their notched engagement with the adjacent portions of the diagonals, to which said boards extend. The notches in the seats are at right angles to their faces and both ends of the seats being symmetrical it is immaterial which side is placed up or down. Any weight on the central area of the seats presses down on the tops of the legs so that undue strain on the bar units at the ends and which would tend to buckle them upwardly at the center is avoided. The seats also prevent upward movement of the bars and collapse of the framework as long as any one seat is occupied.

The table is preferably formed of three parallel sections 12 hinged together for relative downward folding movement, for the same purpose as set forth in my co-pending application for patent, Serial No. 633,233, filed September 15, 1932. The two outermost sections when outstretched are braced against downward buckling by hinged link straps 13 extending between and under said sections, as shown in Fig. 7.

The table sections are provided with a rigid depending flange 14 all around. The inner faces of this flange at the corners of the outer sections wedgingly engage the outer edges of the co-operating pairs of diagonals as shown in Fig. 6. This feature causes the diagonals to be sprung in slightly enhancing the rigidity of the assembled structure as well as positively preventing shifting of the table relative to the frame. This also permits the use of lighter frame material while assuring ample strength and rigidity. This feature is of course obtained by making the table and its surrounding flange slightly smaller in dimensions than the actual distances between the diagonals when the latter are unsprung.

The new arrangement of the parts of the frame structure also enables the same to be folded into a more compact space than was previously the case so that they may be conveniently packed when folded inside the folded table, as shown in Fig. 7 and as particularly set forth in said co-pending application last above mentioned.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims. 75

Having thus described my invention what I claim as new and useful and desire to secure by Letters Patent is:

1. In a folding table and seat unit, a foldable table and seat supporting frame comprising corner legs, table-supporting members converging upwardly toward each other from and abutting against the outer faces of adjacent legs, pivot connections between said legs and members, horizontal seat-supporting bar units disposed outwardly of said members and pivoted thereto, said units each comprising a pair of bars together extending between adjacent legs substantially on a level with the top of the legs, and downwardly folding hinge connections between the adjacent ends of adjacent bars; hinge means connecting adjacent bars of adjacent units, and means between the legs and said hinge means to tie them together when the frame is fully 95 unfolded and arranged so as to spring the legs toward the corresponding ends of the bars.

2. In a folding table and seat unit, a foldable table and seat supporting frame comprising corner legs, table-supporting members converging upwardly toward each other from and abutting against the outer faces of adjacent legs, pivot connections between said legs and members, horizontal seat-supporting bar units disposed outwardly of said members and pivoted thereto, said units each comprising a pair of bars together extending between adjacent legs substantially on a level with the top of the legs, and downwardly folding hinge connections between the adjacent ends of adjacent bars; rigid angle straps abutting against the side faces of and extending between the adjacent ends of adjacent units, hinge pins through said straps and bars, and rigid members secured to the legs and projecting upwardly to engage the outer faces of the straps between the bars when the units are fully unfolded. 110

3. In a folding table and seat unit, a foldable table and seat supporting frame comprising corner legs, table-supporting members converging upwardly toward each other from and abutting against the outer faces of adjacent legs, pivot connections between said legs and members, horizontal seat-supporting bar units disposed outwardly of said members and pivoted thereto, said units each comprising a pair of bars together extending between adjacent legs substantially on a level 130

with the top of the legs, and downwardly folding hinge connections between the adjacent ends of adjacent bars; rigid angle straps abutting against the inner side faces of the 5 adjacent bars of adjacent units at the corners, hinge pins through said straps and bars, and means on the legs for engagement with said straps when the bars are outstretched to hold the legs against possible 10 inward deflection.

In testimony whereof I affix my signature.
IAN MACDONALD.
